UNITED STATES PATENT OFFICE

2,459,853

HOSE PROTECTOR

Lewis H. Swetnam, El Paso, Tex., assignor of
one-half to Howard D. Fulwiler

Application June 25, 1946, Serial No. 679,228

4 Claims. (Cl. 211—113)

1

This invention relates to improvements in garment supporting devices, and more particularly to the provision of a foldable rack for supporting garments for drying purposes.

It is an object of the invention to provide a simple drying rack of few parts, which can be folded to occupy very little space when not in use, and has few parts to get out of order.

A further object is the provision of a simple drying rack, which is foldable, and which has means for supporting wearing apparel of any description, such as underwear, socks, stockings, pants, dresses, coats, etc.

A further object is the provision of a drying rack having means for holding garments in a natural and open condition to allow the free circulation of air through the garments, and an exposure of a greater surface to sunshine.

A further object is the provision of a foldable rack suitable for drying and airing garments quickly and in a proper shape, the rack being especially adapted for use in apartments, schools and colleges, and indoors at home during inclement weather.

These and other objects are attained by the novel construction and arrangement of parts hereinafter described and illustrated by the accompanying drawings, forming a part hereof, and in which:

Fig. 1 is a plan view of a rack embodying the invention.

Fig. 2 is a side view showing the rack supporting garments.

Fig. 3 side view of the rack in a folded condition.

Referring to the drawings, the drying and airing rack is shown to comprise a pair of center bars 1 and 1a, connected at the center of the rack by a hinge 20.

Swivelly connected to the bars 1a and 1, by swivels 21 and 22, respectively, are cross bars 2 and 3.

The outer ends of bars 1 and 1a support triangular loops 31; and similar loops 4 are supported by the outer ends of bars 2 and 3. The loops pass through the finger engaging portions 32 of 5 and 6, which are of the type of clothes pin having a spring to maintain the clothes pin normally closed, the pin being released from a garment by pressure on the portions 32.

A hook or eye 11 is attached to and depends from one of the members of hinge 20, and has supported thereby a triangular loop 8 supporting a clothes pin 7 of the spring type above described.

Referring to Figs. 1 and 2, it will be seen that the center bars 1a and 1, cooperate with the cross bars 2 and 3 to support garments in an open condition to enable the air to freely circulate, and cause the garments to dry in a shapely manner. The cross bars can also be used together with the member 8 and associated parts to provide various combinations to suit garments of different shapes.

2

The structure enables a large number of combinations to enable the drying of socks in an open condition, the drying or airing of lingeries, pants, and garments of every description.

5 A hook 9 is provided by means of which the rack can be hung from a lamp shade, a cord across a room, or in any suitable place available.

In Fig. 3, the device is folded, and occupies very little spaces, enabling it to be stored, when not in use, in drawers, trunks, and enabling it to be conveniently carried in a suitcase when traveling.

The above description is to be considered as illustrative and not limitative of the invention, of which modifications can be made without departing from the spirit and scope of the appended claims.

The invention having been described, what is claimed is:

1. In a garment drying rack, a pair of center bars, a hinge connecting the upper side of one end of each bar, a hook connected to the hinge, an eye depending from the hinge, spaced cross bars swivelly connected to the center bars, triangular loops depending from the ends of the bars and the eye, and clothes pins supported by the loops.

2. In a rack for drying garments, a pair of center bars, a hinge connecting the upper side of one end of each bar, an eye depending from the hinge, spaced cross bars swivelly connected to the center bars, loops depending from the bars and the eye, and clothes pin of a normally closed spring type supported by the loops.

3. In a garment drying rack, a pair of center bars, a hinge connecting the upper side of one end of each bar spaced cross bars swivelly connected to the center bars, an eye depending from the hinge, and means for supporting clothes pins from said bars and eye.

4. In a garment drying rack, a pair of center bars, a hinge connecting the upper side of one end of each bar, a hook connected to the hinge for supporting the rack, an eye depending from the hinge, spaced cross-bars swivelly attached to the center bars, loops supported by the bars and eye, and clothes pins supported by loops, said clothes pins being of a spring type normally closed.

LEWIS H. SWETNAM.
